UNITED STATES PATENT OFFICE.

MAX BAUM, OF NEW YORK, N. Y., ASSIGNOR TO RADICE ELECTRIC CO., INC., A CORPORATION OF NEW YORK.

DESIGN FOR AN ELECTRIC-LIGHT-SOCKET ADAPTER.

Application filed September 6, 1927. Serial No. 23,303. Term of patent 3½ years.

To all whom it may concern:

Be it known that I, MAX BAUM, a citizen of Poland, residing in New York, county of Bronx, and State of New York, and doing business at 19 West Moshula Parkway, in said city, have invented a new, original, and ornamental Design for an Electric-Light-Socket Adapter, of which the following is a

specification, reference being had to the accompanying drawing, forming part thereof.

Figure 1 is a plan view, and
Figure 2 is an edge view.

I claim:

The ornamental design for an electric light socket adapter, substantially as shown.

MAX BAUM. [L.S.]
